UNITED STATES PATENT OFFICE

ALFRED J. BLANCHETTE, OF CHICAGO, ILLINOIS

PROTECTING DEVICE

Application filed July 15, 1929. Serial No. 378,457.

This invention relates to a protecting device designed primarily for use in connection with walls having openings for the passage of the operating levers or rods for semaphore signals, but it is to be understood that a protecting device, in accordance with this invention may be employed in any connection for which it is found applicable, and the invention has for its object to provide, in 5 a manner as hereinafter set forth, a device of such class with shiftable means for permanently closing such openings without retarding the operation of the signal actuating rods or levers.

10 A further object of the invention is to provide, in a manner as hereinafter set forth, a device of the class referred to including shiftable means permanently acting to arrest the entrance of snow or sleet into wall openings through which pass the actuating rods or levers for semaphore signals, thereby preventing any possibility of the jamming 15 of the rods or levers in such openings.

A further object of the invention is to provide, in a manner as hereinafter set forth, a device of the class referred to including shiftable means permanently acting to close the wall openings through which pass semaphore signal actuating rods or levers thereby preventing the passage through such 20 openings of sparks from engines, snow, rain, wind, sleet, cold, resulting in the protecting of the operator of the rods or levers.

A further object of the invention is to provide, in a manner as hereinafter set forth, a device of the class referred to including shiftable means permanently acting to close wall openings employed for the passage of signal actuating rods or levers to prevent 25 any possibility of ice forming around the levers or rods within the openings which otherwise would jam or retard the operation of such rods or levers.

Further objects of the invention are to provide, in a manner as hereinafter set forth, a protecting device for the purpose referred to which is simple in its construction and arrangement, strong, durable, compact, thoroughly efficient in its use, acting as a protector from inclement and cold weather re-

sulting in a saving of fuel consumption, readily assembled, quickly installed in position and comparatively inexpensive to manufacture.

With the foregoing and other objects in view the invention consists of the novel construction, combination and arrangement of parts as hereinafter more specifically described, and illustrated in the accompanying drawings, wherein is shown an embodiment 55 of the invention, but it is to be understood that changes, variations and modifications can be resorted to which fall within the scope 60 of the claims hereunto appended.

In the drawings wherein like reference characters denote corresponding parts throughout the several views:

Figure 1 is a front elevation of a protecting device in accordance with this invention installed with respect to a wall having openings for the passage of signal operating rods.

Figure 2 is a section on line 2—2 of Figure 1.

Figure 3 is a fragmentary view in vertical section of a wall provided with an opening and further illustrating the adaptation of a protecting device in accordance with this invention with respect to the opening and also showing a signal shifting rod and the actuating lever for the rod.

Figure 4 is a fragmentary view in rear elevation of a wall provided with an opening for the passage of a shifting rod for a signal and further showing the adaptation of the protecting device with respect to the wall.

Figure 5 is a fragmentary view in vertical section of a modified form of protecting device.

A protecting device, in accordance with this invention is designed primarily for the closing of an opening or openings formed in the wall or walls of a signalling tower to protect the part or portion of a signal shifting rod or lever arranged within an opening or openings, as well as to protect the signal man within the tower.

The device can be set up with one or more closure members, depending upon the number of wall openings. As illustrated the device 100

is shown with two shiftable closure members. It is to be understood that the number of shiftable closure members will correspond to the number of wall openings. The device is secured to the outer face of the wall.

Referring to the drawings in detail 1 indicates one of the walls of a signalling tower and which is provided with a pair of rectangular openings 2, 3 for the passage of shifting rods 4, 5 respectively. The rods are employed for shifting semaphore signals to and from signalling position. The rods extend into the tower and are connected to actuating levers therefor and such levers are shifted by the signal man stationed within the tower. An actuating lever for one of the shifting rods is indicated at 6.

The device includes a wall plate 7 of the desired size which is secured to the outer face 20 of the wall 1 by the holdfast devices 8. The plate 7 is provided with a pair of rectangular slots 9, 10 which register respectively with the openings 2, 3.

Secured to the outer face of the plate 7 is a 25 pair of spaced, oppositely disposed, opposed, combined guide and retaining bars 11, 12 of equal length. The bar 11 is mortised on its inner face to provide a slide-way 13 and bar 12 is mortised on its inner face to provide a 30 slideway 14.

Slidably mounted against the plate 7 and retained in position by the bars 11, 12 is a pair of closure members 15, 16, the former provided centrally with a vertically disposed slot 35 17 and the latter with a vertically disposed slot 18. The slots 17, 18 register with the slots 9, 10 and the length of slots 17, 18 corresponds to the width of slots 9, 10, respectively. The width of slots 17, 18 is materially less than the width of slots 9, 10 respectively. The closure members 15, 16 are arranged in spaced relation and each of which is capable of being shifted in an outward or an inward direction on the outer face of plate 7. The 45 bars 11, 12 overhang the outer faces of the members 15, 16, and these latter act as permanent closures for the openings 2, 3.

The bars 11, 12 are disposed longitudinally and arranged between bars 11, 12 as well as 50 being secured to the outer face of each closure member is a pair of spaced, vertically disposed combined guide and retaining bars. The pair of bars secured to the outer face of member 15 are indicated at 19, 20 and the 55 pair of bars secured to the outer face of member 16 are indicated at 21, 22. The bars of each pair are oppositely disposed with respect to each other. The bars 19, 20 have their inner faces mortised as at 23, 24 respectively to provide slide-ways. The bars 21, 22 have their inner faces mortised as at 25, 26 respectively to provide slide-ways.

Slidably mounted against the outer face 60 of the member 15 and retained thereagainst by the bars 19, 20 is a vertically movable

plate 27 formed with a central opening 28. Slidably mounted against the outer face of the member 16 and retained thereagainst by the bars 21, 22 is a vertically movable plate 29 having a central opening 30.

Secured to the outer face of the plate 27 is a circular disk 31 provided with an opening 32 which registers with the opening 28. Secured to the outer face of the plate 29 is a circular disk 33 provided with a central opening 34 which registers with the opening 30. The disks 31 and 33 are secured to the plates 27, 29 respectively by the holdfast devices 35. The edges of the disks 31, 33 are spaced from the inner edges of the bars 19, 20, 21 and 22.

The shifting rod 4 extends through the opening 2, slot 9, slot 17 and openings 28 and 32. The rod 5 extends through the opening 3, slots 10 and 18 and openings 30 and 34.

The member 15 and plate 27 prevent the entrance of rain, snow and sleet to the opening 2. The member 16 and plate 29 prevent the entrance of snow, sleet and rain to the opening 3. The members 15 and 16 constitute permanent closures for the openings 2, 3 respectively.

When the rods 2, 3 are shifted the members 15 and 16 are carried therewith. The vertically movable plates 27, 29 prevent any possibility of the jamming of the rods 4, 5. The rods 4, 5 can shift horizontally as well as in a slight vertical direction. The slots in the members 15, 16 in connection with the vertical movement of the plates 27, 29 prevent any binding of the rods 4, 5 on the angular shift of these latter. The wall openings 2, 3 are at all times closed whether the rods 4, 5 be in normal or in shifted position.

The combined guide and retaining bars 105 can be set up in the form as shown in Figure 5, that is to say of angular form to receive ball bearings 35 for a closure member 36. In Figure 5 the combined guide and retaining bar is indicated at 37 and is of angular form. The ball bearings can be positioned at the top and bottom edges of the closure member 36. In Figure 5 the wall plate is designated 38 and the building wall 39. Otherwise than that as stated the form in Figure 5 would be set up in the same manner as shown in Figure 1.

The holdfast devices for securing the bars 11 and 12 to the wall plate 7 are indicated at 40. The holdfast devices for securing the bars 19, 20, 21 and 22 to the members 15 and 16 are designated 41. One of the holdfast devices 8 and which is indicated at 8' provides a stop for the outward movement of the member 15 and another of the holdfast devices 8 and which is indicated at 8'' provides a stop to arrest the outward movement of the member 16.

It is thought the many advantages of a protecting device, in accordance with this in-

vention and for the purpose set forth can be readily understood, and although the preferred embodiment of the invention is as illustrated and described, yet it is to be understood that changes in the details of construction can be had which fall within the scope of the invention as claimed.

What I claim is:

1. In a protecting device for a wall opening through which extends a signal shifting rod, the combination of a plate adapted to be secured to the wall and having an opening registering with the wall opening, a horizontally shiftable inner element opposing the outer face of said plate, a vertically shiftable outer element opposing the outer face of the inner element, said elements permanently closing the openings in said plate and wall, said inner element provided with a slot communicating with the opening in said plate, said outer element provided with an opening registering with said slot, said slot and the openings in said plate and inner element providing for the passage of the shifting rod, horizontally disposed means connected to said plate for slidably supporting said inner element, and vertically disposed means connected to said inner element and slidably connecting said outer element against said inner element.

2. In a protecting device for a wall opening through which extends a signal shifting rod, the combination of a horizontally shiftable inner element, a vertically shiftable outer element, apertured means secured to the wall for slidably supporting said inner element and having its aperture registering with the opening in the wall, means carried by the inner element for slidably connecting said outer element therewith, said elements opposing each other and permanently closing the opening in the wall and the aperture in said means, said inner element provided with a slot communicating with the aperture in said means and the wall opening, said outer element provided with an opening registering with said slot, the aperture in said means, the slot in said inner element and the opening in the outer element providing for the passage of the shifting rod.

3. In a protecting device for a wall opening through which extends a signal shifting rod, the combination of a horizontally shiftable inner element, a vertically shiftable outer element, apertured means secured to the wall for slidably supporting said inner element and having its aperture registering with the opening in the wall, means carried by the inner element for slidably connecting said outer element therewith, said elements opposing each other and permanently closing the opening in the wall and the aperture in said means, said inner element provided with a slot communicating with the aperture in said means and the wall opening, said outer

element provided with an opening registering with said slot, the aperture in said means, the slot in said inner element and the opening in the outer element providing for the passage of the shifting rod, and a disk secured to the outer face of said vertically shiftable element and provided with an opening registering with the opening in such element.

4. In a protecting device for a rectangular wall opening through which extends a signal shifting rod, the combination of a plate adapted to be secured to the wall and having an opening corresponding to the shape of and registering with the wall opening, a horizontally shiftable inner element opposing the outer face of said plate, a vertically shiftable outer element opposing the outer face of the inner element, said inner element having a vertically disposed slot arranged at its vertical median, of a length corresponding to the width and of a width materially less than the length of the opening in said plate, said outer element formed with an opening at the intersection of the vertical and transverse medians thereof and of a diameter corresponding to the width of said slot, means for slidably connecting the outer element to the inner element, means for slidably connecting the inner element to said plate, and the openings in the plate and outer element and said slot providing for the passage of the signal shifting rod.

5. In a protecting device for a rectangular wall opening through which extends a signal shifting rod, the combination of a plate adapted to be secured to the wall and having an opening corresponding to the shape of and registering with the wall opening, a horizontally shiftable inner element opposing the outer face of said plate, a vertically shiftable outer element opposing the outer face of the inner element, said inner element having a vertically disposed slot arranged at its vertical median, of a length corresponding to the width and of a width materially less than the length of the opening in said plate, said outer element formed with an opening at the intersection of the vertical and transverse medians thereof and of a diameter corresponding to the width of said slot, means for slidably connecting the outer element to the inner and means for slidably connecting the inner element to said plate, the openings in the plate and outer element and said slot providing for the passage of the signal shifting rod, one of said means being vertically disposed and secured to the outer face of said inner element, the other of said means being horizontally disposed and secured to the outer face of said plate.

6. In a protecting device for a wall opening through which extends a signal shifting rod, the combination of a plate adapted to be secured to the wall and having an opening

of the same area as and registering with the opening in the wall, a horizontally shiftable member for permanently closing said opening, said member having a vertical slot for the passage of the rod and positioned against the outer face of said plate, a vertically shiftable element positioned against the outer face of said member and having an opening for the passage of the rod, means secured to said plate for slidably connecting said member thereto, means secured to said member for slidably connecting said element therewith, said means arranged on the outer face of said plate and the outer face of said member, the means on the plate disposed at right angles with respect to the means on said member.

In testimony whereof, I affix my signature hereto.

ALFRED J. BLANCHETTE.
